Primary Examiner — Darlington Ly
Assistant Examiner — Giang Hoang Tran(57) **CLAIM**

The ornamental design for an electric motorbike, as shown and described.

DESCRIPTION

FIG. 1 is a front and left side perspective view of an electric motorbike showing my new design;

FIG. 2 is a rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines in the drawings depict portions of the electric motorbike that form no part of the claimed design.

1 Claim, 7 Drawing Sheets(56)
